UNITED STATES PATENT OFFICE.

HERMAN SCHENK, OF BRIERCREST, SASKATCHEWAN, CANADA, ASSIGNOR OF ONE-SIXTH TO HENRY ANDREW McILWAINE, ONE-SIXTH TO WILLIAM HENRY WEDDIE, AND ONE-SIXTH TO EDWARD PRESTON RAE, ALL OF BRIERCREST, CANADA.

STOOKING ATTACHMENT FOR BINDERS.

Application filed February 10, 1927. Serial No. 167,272.

My invention relates to improvements in stooking attachments for binders, which has for its particular objects the provision of means whereby grain is delivered from the knoter of the binder into a basket and from thence to form several sheaves into a stook which is removed from the basket and lowered into standing position in the stubble, such action being attained by arranging the stook grappling mechanism to move rearwardly of the machine when releasing the stook, at a speed coincidental with the forward movement of the machine, so that the stook is relieved of horizontal momentum and is in consequence also relieved of any tendency to fall over on being released from the machine. Further objects are to eliminate all hand labour during the stooking and to provide for the stooks being arranged at predetermined intervals apart on the field, so that the labour of collection prior to separating is reduced to a minimum.

The invention consists essentially of an elevator which receives the sheaves from the binder and deposits them singly into an open basket which is mechanically closed on the actuation of a tripping device, which in turn is either manually or automatically operated, and means for removing the stook from the basket and depositing it in standing position to the rear of the machine, as will be more fully described in the following specification, in which:—

Fig. 1 is a plan view of the stooker, with the elevator mechanism and the grappler mechanism removed.

Fig. 2 is an elevation looking towards the binder with the elevator and basket mechanism removed showing the grappler mechanism in position subsequent to raising a stook (not shown) from the basket.

Fig. 3 is an elevation looking towards the binder with the elevator and basket mechanism and a locking device removed showing the grappler mechanism open after depositing the stook on the ground.

Fig. 4 is a forward side elevation of the elevator with the distributor table mechanism removed and in position to receive a sheaf.

Fig. 5 is a forward side elevation of the elevator with the distributor table mechanism

removed, in position to raise a sheave by the upper tines to the receiving table.

Fig. 6 is an elevation of the elevator with the distributor table mechanism removed, from the binder side with its movement in position shown in Figure 4.

Fig. 7 is an elevation of the elevator with the distributor table mechanism removed, from the binder side with the shields removed, with its movement in position shown in Figure 5.

Fig. 8 is a side elevational view of the distributor mechanism with table fully extended.

Fig. 9 is a side elevational view of the distributor mechanism with the table partially withdrawn.

Fig. 10 is a side view of the distributor mechanism showing the table commencing to lift.

Fig. 11 is a front view of same.

Fig. 12 is a side view of the distributor mechanism showing the table fully raised.

Fig. 13 is a front view of same.

Fig. 14 is a side view of the basket, shown in open position.

Fig. 15 is a side view of the basket, shown in closed position.

Fig. 16 is a plan view of the bell crank movement actuating the side walls of the basket.

Fig. 17 is a sectional view of the clutch operating the elevator mechanism and the stook basket.

Fig. 18 is a front elevation of the bull wheel and its clutches.

Fig. 19 is a sectional view of the clutch operating the grappler mechanism.

Fig. 20 is a detail view of the lifting arm and grappler shield next to the binder, and shown in forward position.

Fig. 21 is a detail view of the lifting arm and grappler shield next to the binder, and shown in rearward position.

Fig. 22 is a plan view of the grappler with its tines open and shown in a position of rest, but with its central movement omitted for clarity of disclosure.

Fig. 23 is an elevation of the grappler as in the position shown in Figure 22.

Fig. 24 is a plan view of the central movement of the grappler omitted from Figure 22.

Fig. 25 is a side view of the grappler in closed position just prior to dropping its stooks.

Fig. 26 is a side view of a lifting arm and shield at the limit of its rearward swing.

Fig. 27 is a side view of the grappler showing it in closed position as during the raising of a stook from the basket.

Fig. 28 is a side view of a lifting arm when 10 moving upward and corresponding to the grappler position as in Figure 27.

Fig. 29 is a detail side view showing the tripping devices for the grappler movement.

Fig. 30 is a detail side view of the tripping 15 devices of the grappler movement.

Fig. 31 is a plan view showing the tripping devices corresponding to Figure 29.

Fig. 32 is a view of a trip mechanism.

In the drawings like characters of reference indicate corresponding parts in each figure.

In the general views of the invention many parts which are shown in detail are omitted to avoid unnecessary confusion.

25 The machine frame generally indicated by the letter A consists of an A shaped member A¹ having at its apex a universal joint A² by which it is adapted for connection to a suitable part of the binder, the base of the member A¹ being secured to longitudinal side frames A³ and A⁴ each of which comprise horizontal members suitably braced by curved or other stays. The side frames A³ and A⁴ are connected together by a rear wheel 30 mounting A⁵ in which a universally pivoted trailer wheel A⁶ is mounted. The frames A³ and A⁴ are cross connected at intervals with transverse members A⁷, A⁸ and A⁹, and a further horizontal frame member, indicated by 35 A¹⁰, extends from the apex of A¹ to the side frame A³. Extending upwards from the transverse member A⁷ is a support A¹¹ which rises above the upper horizontal members of the side member A³ and A⁴ as at A¹², from 40 whence it is carried downwards and then extends in the same horizontal plane as the said horizontal members.

45 The forward end of the lower member of the side frame A³, see Figure 2, is provided with a hinged bracket A¹³ which pivotally supports a jaw A¹⁴ having an inward extension A¹⁵ to which a trip cable A¹⁶ is adapted to be attached, and having also a sheave A¹⁷ at its upper end. Pivotally mounted for vertical movement in the jaw A¹⁴ is a swing arm A¹⁸ which is adapted when operating the stooker on automatic tripping, to extend outwards from the side frame A³ at an angle of 90 degrees, so that as each previously deposited row of stooks is reached by the stooker the swing arm strikes the stook and is swung about its pivot, thereby exerting a tension to the trip line A¹⁶. A line A¹⁹ extends from the swing arm A¹⁸ over the sheave A¹⁷ and 50 is conducted over a suitable arrangement of

devices, not shown, to the operator's seat to enable him to raise the arm out of engagement with the stooks when desired and to fasten it. Supported above the horizontal frame members A¹ and A¹⁰ is a further side 70 frame A²⁰ comprising rails and stays generally similar to the side frames A³ and A⁴, which frame is disposed on the binder side of the stooker between the basket and the elevator mechanism. Extending across the members A¹⁰ are a pair of longitudinal members A²¹ which are adapted to form a base for the elevator mechanism. Journalled between the side frames A³ and A⁴ is a bull wheel shaft 75 A²².

80 The sheaf or bundle elevator consists of a pair of frames B¹ having front legs B² and rear legs B³, the word "front" being used to indicate that portion of the elevator which faces the binder. The upper ends of the 85 frames each support an inclined crescent shaped bracket B⁴, these brackets are connected together by a bar B⁵ at their upper end and by a shaft B⁶ at their lower end, they also support a sheet metal table B⁷. Extending from the bar B⁵ is a curved shield B⁸ formed of strips of material spaced apart, see Figure 6, which connects at its lower extremity to the rear frame legs B³. Extending between the legs B² and B³ are braces B⁹ and 90 B¹⁰, the braces B⁹ being connected by a rod B¹¹, which forms an upper support for a lower shield B¹² comprising curved strips of material spaced apart in a similar manner to the shield B⁸, the outer end of the strips being 95 connected to a further bar B¹³ supported on a pair of braces B¹⁴ erected on the frame members of the machine. The lower portion of the shield B¹² is adapted to lie in a plane below that of the bar B¹³, so as to form a suitable 100 receiving pocket for the sheaves as they are delivered from the binder. Pivotally mounted upon the bar B¹² are a pair of curved tripping levers B¹⁵ which are adapted to extend 105 on opposite sides of the kicker of the binder and when actuated thereby, to move a trip rod B¹⁶ through a link B¹⁷ and a counter lever B¹⁸, as shown. A pair of bearings B¹⁹ are supported on the legs B² in which short 110 aligned shafts B²⁰ and B²¹ are journalled, 115 these shafts are connected together by a pair of cranks B²² having an elongated crank pin B²³. The shafts B²⁰ and B²¹ and their associated parts are driven by mitre gears B²⁴, one 120 of which is keyed to a suitably journalled shaft B²⁵, see Figure 1, which in turn is driven from the bull wheel by a suitable clutch mechanism, which will be described later. Pivotally connected to each of the braces B⁹ are bell 125 cranks B²⁶ which are connected at one end as at B²⁷ to one end of a rod B²⁸ and at the other end as at B²⁹ to a rod B³⁰. B³¹ indicates a 130 plurality of lower tines, which are adapted to project between the vertical spaces of the shield B¹² and to describe the movement 130

shown in dotted line in Figures 4 and 5. These tines are connected together by a bar B³², the outer pair are journalled on the elongated crank pin B²³ and are provided with a 5 rearward extension arm B³³ connected to the lower end of the rod B²⁸. The lower end of the rod B³⁰ is also journalled upon the crank pin B²³ so that as rotation is imparted in an 10 anti-clockwise direction as viewed from the front of the machine, to the shafts B²⁰ and B²¹, the tines are caused to project through the spaces of the shield and lift up any sheaves lying therein, carrying them upwards and inwards towards the frame B¹, when they are 15 delivered to the upper tines which will be hereinafter described, and after such delivery the tines B³¹ are withdrawn behind the shield B¹² and are caused to descend on the completion of rotation of the cranks.

20 Mounted on the shaft B²⁰ is a drive pinion meshing with a driven gear B³⁴ mounted on a shaft B³⁵ journalled between the frames B¹. At opposite ends of the shaft B³⁵ a crank B³⁶ is provided, which actuates connecting rods 25 B³⁷ controlling the sheaf distribution into the basket. Extending between the upper portions of the frames B¹ is a suitably journalled shaft B³⁸ having a plurality of upper tines B³⁹ projecting through the spaces in the upper shield B⁸, which tines are spaced apart by separators B⁴⁰. At one end of the shaft B³⁸ a double grooved sheave B⁴¹ is keyed. On the outer end of the shaft B²¹ is a crank B⁴² having operative engagement with a cable 30 rod B⁴³. Extending from opposite ends of the cable rod are a pair of cables B⁴⁴, each leading around one of the grooves of the sheave B⁴¹ in opposite directions and having their outer ends secured to the sheave, so that 35 the rotation of the crank B⁴² imparts partial rotation in opposite directions to the shaft B³⁸ and causes the upper tines B³⁹ to receive the bundles or sheaves as they reach the upper limit of their elevation on the lower tines B³¹, see Figure 5, and to swing them 40 around the upper shield B⁸ and finally deposit them on the table B⁷. Turnbuckles B⁴⁵ will preferably be provided adjacent opposite ends of the cable rod B⁴³ as a means for adjusting 45 the cable B⁴⁴ so that the upward movement of the upper tines B³⁹ will commence with the commencement of the downward movement of the lower tines B³¹. Free- 50 ly mounted on opposite ends of the shaft B⁶ 55 are a pair of slotted distributers B⁴⁶ which are cross connected by a plate B⁴⁷ forming a hinged extension to the table B⁷, and end- 60 wise movable in the slots of the distributers are pairs of rollers B⁴⁸ between which a fur- 65 ther plate B⁴⁹ extends, forming a bundle spreader. The outer rollers B⁴⁸ of each pair 70 is mounted on a rod B⁵⁰ which extends beyond the distributers B⁴⁶ and is pivotally connected to a pair of rocking arms generally indicated 75 by B⁵¹. At the outer end of the plate or

bundle spreader B⁴⁹ is a rod having a plurality of spring tensioned fingers B⁵² which impose such resistance to the bundles or sheaves as they slide downwards along the table B⁷, the extension B⁴⁷ and the plate B⁴⁹, as to bring 70 them into alignment with the edge of the plate B⁴⁹ before the resistance of the spring tension is overcome and the fingers are depressed to allow the bundles to fall into the basket. Rockingly mounted on opposite ends 75 of the shaft B³⁸ are bell cranks B⁵³ having legs B⁵⁴ and B⁵⁵, the outer ends of the legs B⁵⁴ are connected to the connecting rod B³⁷ and the outer ends of the legs B⁵⁵ are provided with a stop B⁵⁶. A rod B⁵⁷ connects each leg 80 B⁵⁵ intermediate its length to an arm B⁵⁸ which is rockingly mounted on the rod B⁶ at the lower end of the table B⁷, this arm is hingingly connected at its outer end to the 85 rocking arm B⁵¹ as at B⁵⁹.

The rocking arm B⁵¹ is provided with an extension B⁶⁰ which is adapted to engage the stop B⁵⁶ of the bell crank B⁵³ during the time that the distributor mechanism is downwardly extended. For the purpose of maintaining a suitable upward strain upon the distributor a coil spring B⁶¹ is interposed between each rocking arm B⁵¹ and its arm B⁵⁸. As the gear wheel B³⁴ is rotated the bell cranks B⁵³ will be rocked through an 90 arc by the connecting rods B³⁷, the bundle spreader B⁴⁹ will be moved lengthwise of the slotted distributor B⁴⁶, thus allowing the sheaves to fall therefrom at varying distances from the table B⁷, enabling the sheaves to 95 be evenly distributed into the basket prior to forming into stooks. During the cycle of movement of the grappler mechanism it is necessary that the distributor table B⁴⁷ and its associated parts to be upwardly swung 100 about the shaft B⁶ to remove it from the path of travel of the grappler mechanism, and also to prevent the dropping of any sheaves from the table B⁷ during the closing of the basket and the removal of the stuck therefrom. I 105 therefore secure a disc B⁶² upon the bull wheel shaft A²² having a double grooved roller or crank pin B⁶³ which during part of the rotation of the disc is adapted to engage a collapsible arm generally indicated 110 by B⁶⁴, which arm is keyed to a rocking shaft B⁶⁵ extending transversely of the stoker frame to the elevator frame B¹. The arm B⁶⁴ consists of a lever B⁶⁶ keyed to the shaft B⁶⁵ and curved at its outer end to an 115 are coinciding with the path of travel of the roller B⁶³ as at B⁶⁷. At the inner end of the curved portion the upper end of a segment B⁶⁸ is pivotally connected, its lower end being connected as at B⁶⁹ to the outer end of an 120 arm B⁷⁰ pivotally connected to a frame member. The disc B⁶² rotating anti-clockwise see Figures 11 and 13, brings its roller B⁶³ first into contact with the arm 125 B⁷⁰ raising it, and through the segment 130

B⁶⁸ raises the lever B⁶⁶ to the limit of its rocking movement imparting clockwise rotation to the shaft B⁶⁵. During the subsequent movement of the roller the segment 5 B⁶⁸ and the curved portion B⁶⁷ are engaged thereby, but their relative positions remain unchanged until the roller passes out of contact with the outer end of the curved portion B⁶⁷ when the arm B⁶⁴ collapses and falls, allowing the shaft B⁶⁵ to rock in an anticlockwise direction to its previous position. Therefore, according to the present timing 10 of the movement the shaft B⁶⁵ is quickly moved throughout its stroke in one direction and is there held for a predetermined period, when it quickly resumes its former position and again remains stationary until the commencement of another cycle 15 of the disc B⁶². At the elevator end of the shaft B⁶⁵ a lever B⁷¹ is keyed, which engages at its free end, through a rod B⁷², a suitably fulcrumed lever B⁷³, the outer end of this lever is connected by a rod B⁷⁴ to a link B⁷⁵. Keyed to the shaft B⁶ to which the distributor 20 plate B⁴⁷ is fixedly mounted, is an arm B⁷⁶ having a lip B⁷⁷ projecting tangentially therefrom, which arm is connected to the link B⁷⁵ by a pin B⁷⁸. During the major portion 25 of the up or down movement of the rod B⁷⁴ and the corresponding swinging movement of the distributor plate B⁴⁷, the link B⁷⁵ will be in contact with the lip B⁷⁷ of the arm B⁷⁶. The action of the springs B⁶¹ during 30 the lifting of the plate B⁴⁷ will exert sufficient force through the rocking arms B⁵¹ to throw the table beyond its top centre and as 35 the table is brought down on the reversal of the movement of the rod B⁷⁴ its movement will be resiliently retarded by the tension 40 of the springs B⁶¹ and finally stopped by the inner ends B⁶⁰ of the rocking arm B⁵¹ coming into contact with the stops B⁵⁰ of the bell 45 crank levers B⁵⁸, so that a slight upward movement of the rod B⁷⁴ beyond the actual requirement will in no way impair the effective operation of the distributor table and its parts.

The sheaves after leaving the distributor plate B⁴⁷ fall into a basket generally indicated by C², see Figs. 14 and 15, which is mounted on trunnions C³ extending from a pair of opposed curved frame members C⁴ and which are suitably fulcrumed between the main frame members A⁴ and A²⁰. The basket C² is formed with bottom wall C⁵ secured to the curved frame members C⁴, which is provided with a plurality of elongated apertures C⁶ the purpose of which will hereinafter appear. Mounted upon one end of 55 the basket is a curved rear end wall C⁷ comprising a plurality of prongs C⁸ and hingededly connected from the opposite or forward end of the bottom wall C⁵ is a front end wall C⁹ having similar prongs. Secured to the 60 front wall C⁹ is a depending arm C¹⁰ which

is connected at its lower extremity to one end of a rod C¹¹, the opposite end of said rod being pivotally connected to one of the horizontal members of the frame so that as the basket is turned in an anti-clockwise direction or from the position shown in Figure 15, the bottom wall C⁵ will assume a substantially vertical position, the rear wall will become substantially horizontal and the forward end wall will be opened out well beyond the bottom wall position and will come to rest in an outwardly inclined position, so as to permit the free entry of the falling sheaves. The basket is provided with a pair of side walls C¹² which are hinged to the side edges of the bottom wall C⁵. Secured to each curved frame member C⁴ is a curved brace C¹³, the upper end of which is turned over as at C¹⁴ to form a support for a bell crank C¹⁵, shown in plan in Figure 16 which is fulcrumed thereto by a pin C¹⁶. Suitably mounted upon the stoker frame is a transversely rocking shaft C¹⁷ provided at one end with an arm C¹⁸ which extends forward and is adapted to be engaged and disengaged by the double grooved roller B⁶³ on the disc B⁶² as it is rotated, the path of travel of the roller is shown in chain dotted line in Figures 14 and 15. On the shaft C¹⁷ a pair of cranks C¹⁹ is mounted, one on either side of the basket C², each of which is connected at its free end to a rod C²⁰ and which also is connected to a brace C¹³ as at C²¹. Mounted upon the outer end of each of the rods C²⁰ is a segmental guide C²², which is provided with a plurality of apertures C²³ for the purpose of adjustably supporting a pin or stop C²⁴. In each of these guides and fulcrumed upon the free end of each of the cranks C¹⁹ is a further crank C²⁵ which is pivotally connected at its upper extremity to one end of a rod C²⁶, the other end of the rod terminating in an eye C²⁷ engaging a leg C²⁸ of the bell crank C¹⁵. The second leg of the bell crank C¹⁵, indicated by C²⁹ is connected by a short rod C³⁰ to a staple C³¹ secured to a side wall C¹². As the basket is changed from open to closed position by the rocking movement of the shaft C¹⁷ and the consequent movement of the cranks C¹⁹ it will be seen that the free end of each of the cranks C¹⁹ will travel further from the basket trunnion C³ than the upper end of the crank C²⁵, hence this crank must move in a clockwise direction until it reaches the stop C²⁴ when motion will be imparted through the rod C²⁶ to the bell crank B¹⁵ and to the side wall C¹² to incline it inwardly, thereby compressing the upper sides of the stook therein to a convenient form that it may be removed from the basket and deposited on the ground by the grappler mechanism. By this process of inclining the outer sheaves towards the centre of the basket, the stook when deposited on the ground will remain in a standing position. It will

be obvious that the bulk of the sheaves when in the basket will lie in close formation and that they will require to be spread apart before the removal of the stook therefrom. I, 5 therefore, provide a shaft A^{22} between the frame A^4 and A^{20} upon which a plurality of spring tensioned tines C^{33} are mounted, which tines are adapted to project through the apertures C^6 as the basket moves to close, the 10 bottom wall C^5 moving across the tines in such a manner that the base of the sheaves therein is combed and spread towards the forward end wall C^9 by the tines. I may provide a cable C^{34} to the tines which would 15 lead to a point convenient to the operator for the purpose of withdrawing the tines out of action, if desired. As a means for returning the basket to open position after the stook has been removed, a coil spring C^{35} is attached by one end to the arm C^{18} and by the other end to a suitable frame member. 20

Freely mounted upon the shaft A^{22} is a bull wheel D^1 from which motion is imparted to the several mechanisms of the stooker. 25 Mounted on the binder side of and adapted for operative engagement with the bull wheel is a clutch generally indicated by E^1 , see Figure 17, which serves to actuate the elevator mechanism and the basket C^1 . Secured to the 30 bull wheel D^1 is an annular ring E^2 having a plurality of inner peripheral recesses E^3 . Fitting over the ring E^2 and freely mounted on the shaft A^{22} is an annular clutch casing E^4 having a peripheral flange E^5 which serves 35 as chain guard for a sprocket wheel E^6 mounted thereon. The outer peripheral edge of the casing is provided with a plurality of ratchet teeth E^7 , the purpose of which will hereinafter appear. Carried within the casing E^4 is a pair of pins upon which are mounted trip arms E^8 each consisting of a three legged bell crank, the legs being indicated by E^9 , E^{10} and E^{11} respectively, and having an angular recess E^{12} , the sides of which form 40 stops for a pawl E^{13} fulcrumed upon a pin E^{14} . A spring E^{15} is secured at one end to the leg E^{11} and at the other to the pawl E^{13} for the purpose of holding the pawl normally out of contact with any of the recesses E^3 . 45 Mounted on the end closure of the casing E^4 is a pair of brackets E^{16} through each of which a rod E^{17} has sliding movement and which also serves as an abutment for a compression spring E^{18} on the rod. Each rod E^{17} 50 is connected to the free end of one of the legs E^9 of one bell crank on trip arm E^8 and to the free end of the leg E^{10} of the other, and is provided with an abutment collar E^{19} for the spring E^{18} , it is also provided with a pair of collars E^{20} secured thereto on opposite sides of a two armed rocking trip E^{21} , so that a counter clockwise movement imparted to either of the trip arms E^{21} or E^{11} will impart movement to the rods E^{17} (one of which may 55 be omitted) and through the bell cranks E^8

will rock the pawls E^{14} into engagement with some of the recesses E^3 causing the ring E^2 and the clutch casing E^4 to rotate in unison.

Suitably supported from the longitudinal frame members A^4 is a centrally pivoted trip lever E^{22} , the upper end of which is adapted to engage either of the trip arms E^{11} or E^{21} to disengage the pawls E^{14} from the recesses E^3 and having a spring latch E^{23} extending to engage any of the ratchet teeth E^7 to prevent the clockwise movement of the casing E^4 . The trip lever is provided with an adjustable spring tension E^{24} to restore it and its associated parts to normal engaging position as shown after having been withdrawn. The 70 lower end of the lever E^{22} is connected through a bell crank E^{25} (also shown in plan in Figure 17) to the cable B^{16} , see Figure 4, which is pulled, by the action of a sheaf as it is kicked from the binder into the elevator 75 hopper and as it throws down the tripping levers B^{15} .

Secured to the outer face of the sprocket wheel E^6 and concentric therewith is the disc B^{62} which imparts swinging movement 90 to the distributor table of the elevator through the double grooved roller B^{63} as previously described. A chain E^{26} , see Figure 1, operatively connects the sprocket E^6 with a further sprocket E^{27} which is keyed to one 95 end of the shaft B^{25} . From the above description it will be seen that as each sheaf falls into the elevator, throwing down the tripping levers B^{15} and causing the actuation of the clutch, that the sprocket wheel E^6 100 will make a quarter turn, and in so doing will rotate the shaft B^{25} and cause the lower tines B^{21} to elevate the sheaf into the bight of the upper tines E^{29} , the upper tines then swinging over to deliver the sheaf onto the 105 table B^7 . This same movement causes the distributor extension B^{49} to move its position, so that each successive sheaf is dropped into the basket in a different position to that taken by the previous one. The grappler 110 mechanism is actuated by the bull wheel D^1 through the medium of a clutch F^1 , which is designed to make one revolution every time the grappler is tripped, and in so doing to impart a complete cycle of operation to the 115 grappler and its parts. The clutch F^1 , see Figure 19, consists of an annular ring F^2 having inner peripheral recesses F^3 and which is secured to the bull wheel D^1 . Concentrically fitted around the ring F^2 is a 120 casing F^4 , which is secured by its end closure (not shown) to the bull wheel shaft A^{22} . Mounted within the casing F^4 are bell cranks F^5 mounted on a pin F^6 and having legs F^7 , F^8 , and F^9 , the legs F^7 extending through the 125 periphery of the casing and forming a trip arm, the legs F^8 and F^9 of opposing cranks being connected together with spring tensioned rods F^{10} in a similar manner to that employed in the clutch E^1 , for the purpose 130

of moving the pawls F¹¹. Mounted on a suitable portion of the frame member A⁴ is a semi-circular guide member F¹² supporting a compression spring F¹³, which is adapted to bear against a trip lever F¹⁴ pivotally mounted upon the frame, which lever is adapted to engage the trip arm F⁷ of the clutch F¹ to cause it to disengage the pawls F¹¹ from the recesses F⁸ of the ring F² for the purpose of disconnecting the drive of the bull wheel D¹ from the grappler mechanism and conversely, as the trip lever F¹⁴ is moved by a pulling strain on the cable A¹⁶, or a further cable F¹⁵ which operates through a bell crank F¹⁶ (also shown in plan bracketed to the figure) the trip arm F⁷ is released to permit the driving engagement of the clutch F¹ through the pawls F¹¹. A light spring latch F¹⁷ is provided on the trip lever F¹⁴ which is adapted to engage a set of ratchet teeth upon the periphery of the casing F⁴ to prevent its rearward or anti-clockwise movement. The cable F¹⁵ is extended through to a suitable lever or foot pedal on the binder, so that during the first round of the field taken by the binder and its stoker, the operation of the grappler mechanism may be manually controlled by the driver.

The grappler mechanism is adapted to swing about a central shaft G¹ which traverses a portion of the frame of the stoker forwardly and rearwardly which will hereinafter be referred to as the grappler traversing movement, which is shown in Figures 2 and 3. This grappler traversing movement is effected by providing the bull wheel shaft A²² with an outside crank G², on the free end of which a bell crank G³ having legs G⁴ and G^{4A} respectively is mounted, the free end of the leg G⁴ is connected to the free end of a leg G⁵ of a bell crank G⁶ journaled upon one of the horizontal members of the frame A³ as at G⁷, the other leg of the bell crank G⁶, indicated by G⁸ is provided with a swinging arm G⁹, which is provided with a pivotally mounted slide socket G¹⁰ at its free end. Intermediate the length of the arm G⁹ a pin G¹¹ is mounted to which one end of a rod G¹² is connected, its opposite end being connected to the free end of the leg G^{4A} of the bell crank G³, so that as the crank G² is rotated by the bull wheel shaft A²² due to the engagement of the clutch F¹, the slide socket G¹⁰ is caused to follow a path as indicated in dotted lines in Figures 2 and 3 and is lettered X. Rockingly mounted on the pin G¹¹ is an arm G¹³ having connection at its forward end to a rod G¹⁴ which is actuated from the crank G² the rearward end of the arm G¹³ actuates a cable rod generally indicated by G¹⁵. Keyed to the shaft G¹ is a double grooved sheave G¹⁶, the spokes of which are shown broken away to disclose other moving parts, this sheave is partially rotated by a pair of cables G¹⁷ which extend from turn buckles G¹⁸ and pass partly around

the grooves of the sheave G¹⁶ and are secured thereto. At the outer end of the cable rod G¹⁵ is an eye G¹⁹ through which a rod G²⁰ is endwise movable, which rod has a stop G²¹ at one end and is pivotally connected at the other to the rim of the sheave G¹⁶ as at G²². The shaft G¹ extends across the machine and beyond the longitudinal frame members A³, A⁴ and A²⁰ and is journaled in a pair of floating bearings G²³, see Figure 1, immediately carried in rockers G²⁴. In order that a parallel motion may be imparted to the shaft G¹ and the grappler supporting mechanism, the pair of rockers G²⁴, in which the shaft G¹ is journaled, is suspended on a so pair of swing arms G²⁵ journaled on frame braces as at G²⁶ and supported on a further pair of swing arms G²⁷, which are keyed at their lower end upon a transverse shaft G²⁸ journaled upon the longitudinal frame members A³ and A²⁰. A further rocker G²⁹ having a central pin G³⁰ is provided towards the rear of the machine, which is pivotally connected to a suspended swing arm G³¹ and supported on another swing arm G³² both of which arms are journaled on the longitudinal frame A³ as at G³³ and G³⁴ respectively. Freely mounted on the shaft G¹ is a reclining T member generally indicated by G³⁵, its horizontal leg G³⁶ forming a rod connection between the outside rocker G²⁴ (and also the shaft G¹) and the rocker G²⁹, the lower T head G³⁷ is carried vertically downwards and is outwardly cranked to support a pivot pin G³⁸, and the upper T head G³⁹ is carried vertically upwards, terminating in a pair of horizontally opposed arms G⁴⁰. A stiffener G⁴¹ extends diagonally downwards from the horizontal leg G³⁶ of the reclining T member G³⁵ passing beyond the lower T member G³⁷, where it is bent back at an acute angle to the member G³⁷ where it is riveted, the apex of the angle therein supporting a pivot pin G⁴² which will hereinafter be referred to.

From the above description of parts, it will be readily seen that as the cable rod G¹⁵ is moved in a rearwardly endwise direction the sheave G¹⁶ will be rotated anti-clockwise until the stop, G²¹ of the rod G²⁰ is brought into contact with the eye G¹⁹ of the cable rod. When rotation of the sheave will be arrested and the sheave, its shaft G¹ and associated parts will be moved as a unit rearwardly of the machine.

Mounted on the pin G³⁸ at the base of the lower T member G³⁷ is a bell crank G⁴³ having legs G⁴⁴ and G⁴⁵, the leg G⁴⁴ being provided with an eye in which a slide collar G⁴⁶ is pivotally mounted. Extending through the collar G⁴⁶ is a rod G⁴⁷ which is connected at one end to the pin G⁴² of the stay G⁴¹, the opposite end being provided with a stop G⁴⁸ forming an abutment for a compression spring G⁴⁹ which tends to move the bell crank G⁴³ in a clockwise direction. Suitably sup-

ported from the spokes of the cable sheave G^{16} is a rim G^{50} having a coil spring G^{51} around a portion of its periphery, which spring is limited in its expansive movement in opposite directions by stops G^{52} and G^{53} .
 5 Freely mounted upon the shaft G^1 is a swinging arm G^{54} having a pair of pins G^{55} forming a fork which embraces a portion of the rim G^{50} , the outer end of the arm is provided with a plurality of apertures G^{56} to any of which, according to the adjustment required, one end of a connecting rod G^{57} is fitted, the other end of the rod being connected to the outer end of the arm G^{44} of the bell crank G^{43} .
 10 Freely mounted on the shaft G^1 is a further swinging arm G^{58} having a fork G^{59} embracing the rim G^{50} , and which is apertured at its outer end to form an adjustable connection, as at G^{60} , for a connecting rod G^{61} .
 15 Secured adjacent the outer end of the transverse shaft G^{28} is a stop arm G^{62} see Figure 32, which is eyed intermediate its length as at G^{63} and is provided with an abutment G^{64} on its forward edge adjacent its upper end.
 20 Note, this movement is omitted from Figure 3, but is shown as a detached view in Figure 32. Freely mounted on the shaft G^{28} is a trip arm G^{65} which is cranked over adjacent its upper end to assume the same plane as the stop arm G^{62} . This trip arm is provided with a forwardly extending rod G^{66} which projects through the eye G^{63} of the stop arm G^{62} and is spring tensioned therefrom, the outer end of the trip arm is provided with a roller G^{67} and the outer end of the rod G^{66} is provided with an eye G^{68} forming a connection to a pull rod G^{69} , which projects freely through the slide socket G^{10} on the arm G^9 . A stop collar G^{70} is secured to the rod G^{69} and is so adjusted that when the arm G^9 is moved to its most forward position as shown in Figure 2, the stop lever G^{62} will be actuated and through the transverse shaft G^{28} the upstanding swing arms G^{27} will be correspondingly moved forward, carrying the cable sheave G^{16} and its shaft G^1 to the position shown in Figure 2. When the above enumerated parts are moved to the limit of their travel in a rearward direction, the stop lever G^{62} and the trip arm G^{65} are temporarily locked in the position shown in Figure 32 by a latch generally indicated by G^{71} , see also Figure 32, and which is supported on a semi-circular bracket G^{72} mounted upon the lower frame member A^3 . Pivotedly mounted upon the bracket is a two piece rearwardly curved arm G^{73} in which a forwardly curved latch G^{74} is pivoted, this latch is provided with a tongue G^{75} at its upper extremity along which the stop lever G^{62} is led into engagement under the bight of the curve, the latch being adapted to come to rest in contact with the stop G^{64} . On the lower end of the latch a spring tensioned trigger G^{76} having a limited upward movement is pivotally mounted, which

is adapted to be tripped downwards on being struck by the roller G^{67} of the trip arm G^{65} on its rearward movement and to subsequently hold the roller against forward movement until an appreciable strain is imposed by the 70 roller due to the forward movement of the rod G^{69} , when such strain tips the latch G^{74} in an anti-clockwise direction to release the stop lever G^{62} and permit the clockwise movement of the transverse shaft G^{28} . The adjustment of the two piece arm G^{73} is effected by providing a stop G^{77} upon the bracket G^{72} . A strong coil spring G^{78} is provided between the upstanding swinging arm G^{27} and a suitable part of the frame for assisting the forward movement of the shaft G^1 and its parts, and also for the purpose of cushioning the final return movement thereof.
 75

Keyed upon the shaft G^1 is a pair of lifting arms G^{80} between which the grappler is adapted to be moved, these arms are outwardly flared at their upper ends to provide arcuate tracks G^{81} formed to a radius from the shaft G^1 , and which terminate in a pair of upstanding brackets G^{82} for supporting shields G^{83} 90 shown removed from Figures 2 and 3, and shown in detail in Figures 20, 21, 26 and 28.

Freely mounted upon the shaft G^1 is a sleeve G^{84} , see Figure 1, having at its extremities a pair of arms G^{85} which support at their 95 upper ends a grappler shaft G^{86} , said shaft extending outwards from the arms to form engagement with the track G^{81} of the lifting arms G^{80} . The outer end of the shaft G^{86} , see Figure 2, is provided with a T member G^{87} having opposed cross arms G^{88} which are connected by connecting rods G^{89} to the cross arms G^{90} of the upper T member G^{89} , so that as the lifting arms G^{80} are swung about the shaft G^1 by the cable sheave movement, the 100 shaft G^{86} of the grappler mechanism is unrotatingly carried about the arc described by the lifting arms and is also permitted a further length of travel corresponding to the length of the arcuate track G^{81} . The path of 110 travel described by the shaft G^{86} is shown in dotted line in Figures 2 and 3, and is designated by the letter W .

It will be understood that since the grappler movement is intermittent, and that periods of 115 rest occur when sheaves are being transferred from the binder, over the elevator of the stoker and into the basket, that the crank G^2 and the associated parts by which the grappler is moved must assume a predetermined 120 position of rest. The position of rest for the crank G^2 and other parts is indicated by a small circle and a letter as follows:—crank G^2 as “ z ”; inner end of cable rod as “ y ”; sliding block G^{10} as “ x ”; lower end of rod G^{20} as “ w ”; upper end of rod G^{20} as “ v ”, and position of grappler shaft G^{86} as “ u ”.
 125

As the arm G^9 is moved towards its most forward position so that the slide socket G^{10} engages the stop G^{70} , the rod is forwardly 130

moved thus raising the trip arm G^{65} to cause the release of the latch G^{74} from the stop arm G^{62} which permits the shaft G^{28} to turn, imparting forward movement to the rockers G^{24} and to the shaft G^1 . The rotation of the shaft G^1 is as previously stated, effected through the movement of the cable rod G^{15} , its cables G^{17} and the sheave G^{16} . The springs G^{51} and G^{49} serve to counterbalance the weight of the grappler, the lifting arms G^{80} and other associated parts and to hold them when desired in the position of rest indicated by "u" in figure 3, during which time the fork G^{59} of the arm G^{58} will be in engagement with one end of the spring G^{51} and through this engagement and the movement of the connecting rod G^{61} , the bell crank G^{43} will impose a compressive strain upon the spring G^{49} . When the grappler is raising its load, the rearward end 20 of the spring G^{51} will abut the fork G^{59} of the arm G^{54} moving it in a clockwise direction, imparting a pulling strain on the connecting rod G^{57} and through the bell crank G^{43} again impose a compressive strain upon the spring G^{49} . The position of the several parts shown in figure 3 is that in which they would be immediately prior to coming to rest or in other words that where the trip arm F^7 of the clutch F^1 is coming into engagement with the trip lever F^{14} and is being lifted to disconnect the drive between the clutch and the shaft A^{22} . It will be noticed that the weight of the several parts being off centre at the period of rest, that a tendency would exist to rotate the clutch casing F^4 in an anti-clockwise direction, but that this is prevented by the spring F^{17} engaging the ratchet teeth F^{18} on the clutch casing.

On the inner faces of the grappler shields G^{83} , see Figures 20 and 21, is a series of guides arranged in opposed pairs, the outer guide G^{90} extending approximately one half of the length of the forward side of each shield, an inner guide G^{91} running parallel thereto, and inwardly curving towards the track G^{81} as at G^{92} , and also an upper guide G^{93} in the form of a triangular member having a convex front surface G^{94} , a concave upper surface G^{95} and a concave surface G^{96} , the triangular member being pivotally mounted on the shield as at G^{97} and resiliently held in position by a spring G^{98} whereby the surfaces G^{91} and G^{94} form a continuous track. Mounted upon the upper end of each of the lifting arms G^{80} is an upwardly spring pressed arm G^{99} having a latch G^{100} intermediate its length and adjacent the forward end of the arcuate track G^{81} , also having at its outer end a roller G^{101} which is adapted to be moved between the guides G^{90} and G^{91} . The purpose of the above mentioned guides and the arm G^{99} will hereinafter appear.

The grappler see Figure 23, which is generally designated by H^1 consists of a frame 65 having longitudinally disposed members H^2

secured adjacent opposite ends of the shaft G^{86} , from the ends of which members a pair of A frames H^3 extend upwards and slope towards each other, the upper ends of the A frames being connected together by a transverse member or head H^4 . Centrally disposed between the shaft G^{86} and the head H^4 a vertical tubular post H^5 is rotatably mounted which is provided with opposed pairs of slots H^6 adjacent its opposing ends. Secured within the post and capable of projection through the slots H^6 are pairs of lower and upper spring mounted catches H^7 and H^8 respectively, see detail in Figure 29, the purpose of which will herein-after appear. Extending also between the shaft G^{86} and the head H^4 is a pair of vertical guides H^9 (shown only in Figure 22) upon which an upper crosshead H^{10} is slidably movable. The lower crosshead H^{11} is slideable upon the post H^5 . The upper crosshead H^{10} is provided at its ends with stub shafts H^{12} to which are fitted rollers H^{13} for the purpose of engaging the guides on the shields of the lifting arms G^{80} for reciprocating the crosshead H^{10} upon the post H^5 . Between the ends of the longitudinal members H^2 are a pair of transverse shafts H^{14} upon each of which a pair of bales or stuck pressers H^{15} , mounted on brackets H^{16} , are hingingly carried. Hingingly connected to each bracket H^{16} is a frame H^{17} carrying a plurality of lower tines H^{18} , the tines H^{18} being hereinafter referred to as the gang tines. The gang tines H^{18} and the bales H^{15} are flexibly tensioned apart by rods H^{19} passing through orifices in the frame H^{17} as at H^{20} and the central portion of the bale H^{15} , which rod is provided with a stop at opposite ends as at H^{21} and H^{22} , between which and the apertured portion H^{20} of the frame H^{17} springs H^{23} and H^{24} are mounted, so that as the pairs of gang tines H^{18} are moved towards each other into the stuck, the springs H^{23} exert a yielding pressure upon the bales H^{15} and compress the head of the stuck, and reversely as the gang tines are removed from engagement with the stuck before the head thereof is released, thus permitting the base of the stuck to spread evenly from internal pressure, in such a manner that it will stand erect in the stubble after being finally released.

Hingingly mounted on each transverse shaft H^{14} is a cranked double arm H^{25} , see Figure 24, which extends on opposite sides of the post H^5 and is connected at its outer end by a rod H^{26} to a gang tine frame H^{17} , each of these double arms is connected to one side of the cross head by a fork member H^{27} , which, like the double arms H^{25} , extend on opposite sides of the post H^5 . The cross head H^{11} to which connection is made to the fork members H^{27} is provided with a slot H^{28} through which the spring catches H^7 are adapted to pass freely. The upper cross head 130

H¹⁰ is provided with a pair of bearing blocks **H²⁹** which are slidable upon the guide posts **H⁹**. A shaft **H³⁰** extends from opposite sides of each of the guide blocks **H²⁹**. Note, these 5 shafts are omitted from Figure 24. A pair of arms **H³¹** are hingingly mounted on each of the shafts **H³⁰**, which are connected at their outer ends to an arm **H³²** which in turn is connected to the lower crosshead **H¹¹**. The arms 10 **H³¹** are upwardly tensioned by a set of springs **H³³** which are of such strength as to bring the crossheads **H¹⁰** and **H¹¹** into intimate relation and to open the grappler by separating the sets of gang tines **H¹⁸** when 15 the weight of the grappler is supported only from the rollers **H¹³** of the upper crosshead. The grappler parts thus far described function in the following manner.

When the grappler is at rest, as shown in 20 Figures 22, 23 and 24, the shaft **G⁸⁶** upon which it is normally supported, is carried at the extreme left of the arcuate track **G⁸¹** of the lifting arms **G⁸⁰** and the rollers **H¹³** of the upper crosshead are at the extreme left of the 25 convex portion **G⁹⁴** of the triangular guides **G⁹³** on the shields **G⁸³**. As the lifting arms are carried over in a forward direction the grappler will maintain its vertical position, the rollers **H¹³** passing out of contact with the 30 shield guides and following a path as shown in Figure 20, subsequently re-entering the shields, reaching a point indicated by a dotted line circle and indicated by the letter "t", when both crosshead guides **H¹⁰** and **H¹¹** are allowed to fall freely along the post **H⁵** and the 35 guide posts **H⁹** by means which will herein-after be described, to the position shown in full line circle and marked **H¹²** in Figure 20, the weight of the crossheads, the bales **H¹⁵**, the gang tines **H¹⁸** and associated parts being sufficient to drive the tines **H¹⁸** between the 40 prongs of the basket **C¹** to engage the stock therein. In this latter position it will be noticed that the shaft **G⁸⁶** having been carried over the centre of the cable sheave shaft **G¹** 45 has slid along the arcuate tracks **H⁸¹** to their opposite end or the extreme right, and in so doing has depressed the levers **G⁹⁹** and has become locked in that position by the catches **G¹⁰⁰** thereof. On the return or rearward 50 movement of the lifting arms **G⁸⁰**, the rollers **H¹³** move along the guides **G⁹²**, raising the triangular guide members **G⁹³** and in entering between the guides **G⁹⁰** and **G⁹¹** come into contact with the rollers **G¹⁰¹** of the lever **G⁹⁹** depressing 55 it far enough to disengage the latches **G¹⁰⁰** from the shaft **G⁸⁶**. When this point is reached by the rollers **H¹³** the arms are at their lowermost position on the rear or 60 anticlockwise movement, therefore, since the support of the latches **G¹⁰⁰** is removed from under the shaft **G⁸⁶** and the arcuate tracks **G⁸¹** are disposed in a substantially vertical position, the grappler, spring supported only by 65 the upper crosshead **H¹⁰**, is free to fall, its

shaft **G⁸⁶** sliding without obstruction downwards of the arcuate tracks **G⁸¹**. The lower crosshead **H¹¹** is held by the spring catches **H⁷** until an appointed time, when the post **H⁵** is turned 90 degrees about its axis by a movement to be hereinafter described, thus releasing the crosshead **H¹¹**, allowing it to be raised and withdrawing the gang tines **H¹⁸** and the bales **H¹⁵** from the stock, permitting it to fall freely into standing position on the stubble. 70 The grappler is unaffected by the further movement of the lifting arm as their movement is continued to the point of rest, except that the rollers **H¹³** are moving at a constant radius from the shaft **G⁸⁶** along the guides **G⁹⁴** to the position shown in Figure 21. The crosshead **H¹¹** is adapted to slide lengthwise of the post **H⁵**, depressing and passing over the spring catches **H⁷** on its downward stroke and the catches **H⁸** on its upward stroke, the 80 catches springing outwards to prevent its return movement. The release of the crosshead is effected by turning the post **H⁵** 90 degrees about its axis so as to bring the catches into alignment with the slots **H²⁸** of the crosshead, that it may pass freely over them. This turning movement is effected by fitting a 85 crank **H³⁴** at the base of the post **H⁵**, which is coupled by a rod **H³⁵** to a spring tensioned lever **H³⁶** fulcrumed in a suitable position on the grappler frame as at **H³⁷**. The free end of the lever **H³⁶** is curved as at **H³⁸** and supports a yoke **H³⁹** which is adapted to stand normally with its opening disposed transversely of the grappler frame and which is pivoted upon a pin **H⁴⁰** and is provided with a recess **H⁴¹** on its rear edge. A dog **H⁴²** of a trigger **H⁴³**, also carried on the lever **H³⁶**, is adapted to engage the recess **H⁴¹** to hold the yoke in normal position. Suitably supported 90 from the grappler frame is a stop **H⁴⁵** which the trigger **H⁴³** is brought into contact with as the lever is moved over by the grappler trip mechanism for the purpose of withdrawing the dog from the recess of the yoke and permitting said yoke to turn at right angles to its 95 normal position, when the lever can return to its starting position as shown in Figure 31. A tension spring **H⁴⁴** is provided between the trigger and the yoke for the purpose of first holding the yoke in extended position and after release for holding it in right angular position, so that it may be again engaged by the tripping mechanism and restored to, and 100 locked in normal position.

The grappler tripping mechanism is generally designated by **J¹** and consists of a pair of ring or plate members **J²** supported by stays **J³** from the outer side members **H²** of the grappler **H¹**. Rockingly mounted between the members **J²** is a bell crank **J⁴** having a horizontal leg **J⁵** and a vertical leg **J⁶**, the leg **J⁵** is slightly curved on its under side as at **J⁷** to provide a variable point of contact for its stop to be referred to later. The upper 110

leg J^6 of the bell crank is inwardly curved as at J^8 to pass over the shaft G^{86} of the grappler and is provided with an upstanding roller J^9 which is adapted to alternately engage, and be released by the yoke H^{39} . Extending between the suitable horizontal members of the frame A^4 are braces J^{10} and J^{11} which are provided with a plurality of adjustment orifices J^{12} and extending between these braces is an apertured bar J^{13} having a roller J^{14} at its forward end which is adapted to form a stop against which the bell crank leg J^5 is brought into contact as the grappler is lowered over the basket, to swing the bell crank in a clockwise direction and through the movement of its roller J^9 to release the lower crosshead H^{11} to permit the grappler to close about the stock in the basket. The bar J^{13} is secured in any desired position by inserting bolts through its apertures and the apertures J^{12} of the braces J^{10} or J^{11} .

An adjustable tension spring J^{14} is connected between the bell crank J^4 and a suitable part of the ring J^2 , which is adapted to return the bell crank to its normal position on the initial lifting of the grappler. During this return movement of the bell crank the roller J^9 is caused to enter the yoke H^{39} to its outwardly extending position, where it is held by the dog H^{42} of the trigger H^{43} .

The means for operating the trip mechanism J^1 during the time when it is required to release the gang tines H^{18} from the stock, see Figure 29, is designated generally by K^1 and consists of a pair of guides K^2 between which a flanged roller K^3 is movable, the roller being of slightly less diameter than the space between the guides. A rod K^4 is supported adjacent its outer end by the roller K^3 and is provided at its outer end with a horizontally mounted roller K^5 which latter is adapted to engage the concave side of the curved upper end J^8 of the bell crank J^4 . The inner end of the rod K^4 is apertured for adjusting purposes as at K^6 and is connected adjacent the outer end of an arm K^7 . The arm K^7 is swingingly mounted on a pin K^8 on the outer side of the arm G^{85} and is provided at its outer end with a contact roller K^9 . Mounted on the pin K^8 is an arcuated member K^{10} having a compression spring K^{11} connected indirectly to the swing arm G^{85} for the purpose of permitting a limited movement to the member K^{10} . A tension spring K^{12} is adjustably connected intermediate the length of the arcuate member K^{10} as at K^{13} and is connected to the arm K^7 . This spring is of such strength as to restore the rod K^4 to its outward position and to bring the arm K^7 into engagement with the free end K^{14} of the arcuate member K^{10} . Hingingly mounted upon one of the longitudinal frame members is an arm K^{15} (see Figures 29 and 3) having its outer end curved as at K^{16} and

fitted with a roller K^{17} which is adapted to engage the roller K^9 and the arm K^7 . The arm K^{15} is provided with a suitable stop to limit its forward movement and is also provided with a spring K^{18} of a tension sufficient to cause the rod K^4 to be held stationary as the lifting arms G^{80} , the grappler and its parts are moved rearwardly subsequent to the completion of their anti-clockwise movement. By this means the bell crank J^4 is swung over and through the yoke H^{39} and the lever H^{36} , the post H^5 being again moved about its axis, this time releasing the lower crosshead H^{11} and permitting it to be raised into close proximity with the upper crosshead H^{10} by the coil springs H^{23} , which action causes the gang tines H^{18} to be withdrawn from the stock.

Having thus described the several parts of my invention and their separate functions, I will now briefly describe its co-ordinated operation.

During the first round of the field the driver of the binder actuates the tripping mechanism of the clutch F^1 by exerting a pull on the cable F^{15} at intervals as desired, thereby enabling the clutch to engage during one revolution of the bull wheel and to rotate the cranks G^2 and the disc B^{62} , through which, motion is imparted to the grappler traversing movement, the grappler swinging movement, its grappling and releasing movement and also to the lifting movement of the distributor B^{47} and the tipping of the basket.

After a row of stocks has been deposited at suitable distances around the field, the line A^{19} is slackened by the driver to permit the swing arm A^{18} to extend at right angles from the stooking attachment so that as the binder and its attachment proceed around the field each stock previously deposited is successively struck by the swing arm A^{18} , causing it to be deflected as the stock is being passed and the line A^{16} connecting the inner end of the swing arm and trip lever F^{14} to be tensioned to actuate the clutch F^1 and to perform automatically the cycle of movements above referred to.

The sheaves, as they leave the binder, fall into the receiving pocket of the elevator, but in so doing depress the tripping levers B^{15} and through the trip rod B^{16} and the trip lever E^{22} bring the clutch E^1 into operative engagement with the bull wheel D^1 for 90 degrees of its rotation, when the clutch is disengaged by the subsequent trip arm E^{11} or E^{21} , each cycle of clutch movement lifts a sheave by the lower tines B^{31} into the bight of the upper tines B^{39} and deposits the previous sheaf from the upper tines onto the table B^7 , where it is allowed to fall into the basket C^2 , at each subsequent cycle the distributor B^{47} is extended or withdrawn so that the sheaves falling into the basket shall assume different places.

At predetermined intervals of the rotation

of the clutch F¹ and the double grooved roller B⁶³ carried thereby, the distributor table B⁴⁷ is elevated to permit the unobstructed movement of the grappler and its parts and also to close the basket about the sheaves therein, to upset the basket, to spread the base of the stuck therein and to compress its head in such a manner that it can be seized by the grappler and removed from the basket prior to its being deposited upon the ground

in a standing position. The rotation of the disc B⁶² and its roller B⁶³, and also that of the crank G² being simultaneous, it will readily be seen that all the movement of the separate mechanism will be so co-ordinated as to bring the basket into upset position during the forward stroke and opening movement of the grappler, to compress the sides of the stuck as the grappler closes about it to lift it, and to raise the grappler and its stuck, swinging it rearwardly at the same time as the distributor B⁴⁷ is being lowered and as the basket is being opened into receiving position.

25 What I claim as my invention is:

1. A stooking attachment adapted for attachment to a binder comprising a frame having a bull wheel and a sheaf receiving basket, means for delivering the sheaves from the binder into the basket, means for upsetting the basket and its sheaves, means for removing the sheaves as a stuck from the basket and for moving the stuck rearwardly of the machine to deposit it in standing position in the stubble, and means for overcoming the horizontal momentum of the stuck during deposition.

2. A stooking attachment adapted for attachment to a binder comprising a frame having a bull wheel and a sheaf receiving basket, means for delivering the sheaves from the binder into the basket, means for upsetting the basket and its sheaves, means for removing the sheaves as a stuck from the basket and for moving the stuck rearwardly of the machine to deposit it in standing position in the stubble, and sheaf distributing means functioning to cause each sheaf delivered to the basket to take a position in the basket different from that occupied by a previously delivered sheaf.

3. A stooking attachment adapted for attachment to a binder comprising a frame having a bull wheel and a sheaf receiving basket, means for delivering the sheaves from the binder into the basket, means for upsetting the basket and its sheaves, means for removing the sheaves as a stuck from the basket and for moving the stuck rearwardly of the machine to deposit it in standing position in the stubble, and means for compressing the upper sides of the stuck prior to its removal from the basket.

4. A stooking attachment adapted for attachment to a binder comprising a frame hav-

ing a bull wheel and a sheaf receiving basket, means for delivering the sheaves from the binder into the basket, means for upsetting the basket and its sheaves, means for removing the sheaves as a stuck from the basket and for moving the stuck rearwardly of the machine to deposit it in standing position in the stubble, and means for spreading the base of the stuck prior to its removal from the basket.

5. A stooking attachment adapted for attachment to a binder comprising a frame having a bull wheel, an elevator, a sheaf receiving basket and a grappler, a receptacle to which the sheaves are successively delivered from the binder, means operable coincident with the delivery of a sheaf to said receptacle for setting the elevator in motion to raise the sheaf and deposit it in the basket, means for upsetting the basket when a predetermined number of sheaves have been deposited therein and for forming a stuck thereof, and means for operating the grappler to raise the stuck from the basket for deposit upon the stubble, and means for returning the basket to sheaf receiving position.

6. A stooking attachment adapted for attachment to a binder comprising a frame having a bull wheel, an elevator to which the sheaves are successively delivered by the binder, a sheaf receiving basket adapted to receive sheaves from the elevator to form a stuck, a grappler, means operable with each delivery of a sheaf to the elevator for setting the elevator in motion to raise the sheaves step by step and to deliver them into the basket, means for upsetting the basket, and means causing the grappler to raise the stuck from the basket and deposit it upon the stubble, and means for returning the basket to sheaf receiving position.

7. A stooking attachment adapted for attachment to a binder comprising a frame having a bull wheel, an elevator to which sheaves are successively delivered by the binder, a sheaf receiving basket and a grappler, means operable coincident with each delivery of a sheaf to the elevator for setting the elevator in motion to raise the sheaf and deposit it in the basket, means for upsetting the basket when a predetermined number of sheaves have been deposited therein and for forming a stuck thereof, and means cooperating with a previously deposited stuck for setting in motion the grappler to raise the stuck from the basket and deposit it upon the stubble and to return the basket to sheaf receiving position.

8. A stooking attachment adapted for attachment to a binder comprising a frame having a bull wheel, a normally open basket adapted to receive sheaves, means for upsetting the basket to form the sheaves into a stuck, and means actuated by the bull wheel for raising the stuck from the basket and

lowering it into proximity with the ground, means for moving the lowered stook rearwardly at the same speed as the attachment is moving forwards, means for releasing the stook and for returning the basket to normally open position.

9. A stooking attachment adapted for attachment to a binder comprising a frame having a bull wheel, a sheaf elevator to which sheaves are successively delivered by the binder, a basket adapted to receive sheaves, and means for removing the sheaves from the basket in the form of a stook and for depositing the stook in standing position on the stubble, said elevator having a distributor, means operable coincident with each delivery of a sheaf to the sheaf elevator for setting the latter in motion to elevate the sheaves step by step onto the table, and means for moving the distributor to deliver the sheaves in different positions within the basket.

10. In a stooking attachment for binders, the combination of a receptacle to which the sheaves are delivered from the binder, a normally idle elevator operable coincident with each delivery of a sheaf to the receptacle for engaging and raising said sheaf, an elevated table to which the sheaves are successively delivered by the elevator, a normally open and horizontally disposed stook forming basket arranged below the table to receive the sheaves therefrom, periodically operable means functioning to upend and to manipulate said basket to dispose the contained sheaves in upright position and in stook formation, a grapple mechanism and means for periodically operating said grapple mechanism to cause said mechanism to lift the stook from the basket and to subsequently move the stook rearwardly to deposit the same upon the ground.

11. In a stooking attachment for binders, the combination of an elevator to which the sheaves are successively delivered from the binder, an elevated table to which the sheaves are successively delivered by the elevator,

means operable coincident with each delivery of a sheaf to the elevator for setting the latter in motion to effect delivery of the sheaves to said table and a stook former into which 50 the sheaves are periodically dropped from the table.

12. The combination with the structure recited in claim 11 of a sheaf distributor associated with said table and functioning to 55 cause each sheaf delivered from the table to the stook former to take a position in the latter different from that occupied by a previously delivered sheaf.

13. In a stooking attachment for binders, 60 the combination of an elevated table, an upper set of vertically swingable sheaf elevating tines arranged to deliver to said table, a lower set of sheaf elevating tines to which the sheaves are successively delivered from 65 the binder, means operable coincident with each delivery of a sheaf to the lower set of tines for setting the latter in motion to deliver the sheaf to the upper set of tines for delivery to said table by subsequent vertical 70 swinging movement of said upper set of tines, a stook former into which the sheaves are dropped from the said table, and means for tining and controlling the operation of said tines.

14. In a stooking attachment for binders the combination of a normally open and horizontally disposed stook forming basket, means for effecting successive delivery of sheaves in horizontal position to said basket, 80 means operable, when the desired number of sheaves have been placed in the basket, for closing the basket about the sheaves and disposing the basket in upright position, a grapple mechanism, and means for operating said grapple mechanism to cause the same to seize the upended sheaves contained in said basket and to deposit the said sheaves, as a stook, upon the ground.

Dated at Briercrest, Sask., this 26 day of 90 November, 1926.

HERMAN SCHENK.
